(57) **CLAIM**

We claim the ornamental design for a column cover, as shown and described.

DESCRIPTION

FIG. 1 is a perspective view of a column cover of our design. FIG. 2 is a front elevational view of the column cover shown in FIG. 1, where the column cover is positioned around a column.

FIG. 3 is a top plan view of the column cover shown in FIG. 2, where the column cover is positioned around a column.

FIG. 4 is a bottom plan view of the column cover shown in FIG. 2, where the column cover is positioned around a column.

FIG. 5 is a left side elevational view of the column cover shown in FIG. 2, where the column cover is positioned around a column.

FIG. 6 is a bottom and left perspective view of the column cover shown in FIG. 2, where the column cover is positioned around a column; and,

FIG. 7 is a bottom and left perspective view of the column cover shown in FIG. 2, where the column cover is positioned around a column and where the column cover is included with additional columns having column covers.

The broken lines in the figures show portions of the column cover which form no part of the claimed design.
